(57) **CLAIM**

The ornamental design for a watering hose, as shown and described.

DESCRIPTION

FIG. 1 is a front perspective view of a watering hose showing a first embodiment of our new design;

FIG. 2 is a side view thereof, with the opposite side being a mirror image thereto;

FIG. 3 is an end view thereof, with the opposite end being a mirror image thereto;

FIG. 4 is a top view thereof;

FIG. 5 is a bottom view thereof;

FIG. 6 is a front perspective view of a watering hose showing a second embodiment of our new design;

FIG. 7 is a side view thereof, with the opposite side being a mirror image thereto;

FIG. 8 is an end view thereof, with the opposite end being a mirror image thereto; and,

FIG. 9 is a top view thereof, with the bottom view being a mirror image thereto.

The broken line disclosures of the internal hose diameter and structure is for illustrative purposes only and form no part of the claimed design.
